UNITED STATES PATENT OFFICE.

HARRY E. MCCOY, OF BEECHVIEW, PENNSYLVANIA, ASSIGNOR TO THE McDOWELL MANUFACTURING COMPANY, OF PITTSBURGH, PENNSYLVANIA, A CORPORATION.

BALL-SHOOTING TOY.

Application filed March 22, 1928. Serial No. 263,928.

This invention relates to mechanical toys, and more particularly to a mechanical toy which can be operated as a game and wherein one or more balls are impelled over a pan or 5 similar object. According to the invention it is proposed to place movable targets out of the normal path of travel of the balls, said targets being so located as to be hit by the balls when gravity acting against centrifugal 10 force pulls the balls out of their normal path of travel.

The invention further contemplates the provision of a target of novel construction in the form of an aeroplane which is free to roll over 15 the surface of the pan or other game board.

The invention may be understood by reference to the accompanying drawings in which a preferred embodiment of the invention is shown, and wherein

20 Figure 1 is a plan view of a toy embodying my invention;

Figure 2 is a transverse vertical section in the plane of line II—II of Figure 1; and

25 Figure 3 is a plan view of the blank from which one of the toy aeroplanes is formed.

In the drawings 2 designates a dish-like pan having an upstanding flange 3 around its periphery, the edge of the flange being curled over. At the center of the pan there may be 30 a flat portion 4, although this is not necessary.

35 Mounted on a pin 5 secured to the pan 2 is the shank 6 of a spinner disk 7. The disk 7 is preferably of a relatively heavy metal and the lower surface thereof is preferably convex, as best shown in Figure 2. The disk 7 is enclosed in a housing 8 with a downwardly turned flange 9 thereon. The housing 8 and the flange 9 completely enclose the disk except that at one side of the housing is a 40 passageway 10 and at the other side of the housing is a passageway 11. By reference to Figure 1 it will be seen that the passageways 10 and 11 are in the form of curved extensions at opposite sides of the housing and these passageways are substantially concentric with the flange 3 of the pan. It will also be seen that the edge of the disk 7 is spaced only a slight distance away from the flange 3. On the under side of the pan are one or more lugs 12.

45 These lugs cause the pan to set at an angle on a flat surface with the portion of the pan where the disk and housing are located at the lowest part of the pan. When the pan is set on the flat surface the top of the housing 8 is substantially horizontal, as shown in Figure

2. The shank 6 of the disk 7 projects above the housing and may have a string 13 secured thereto and adapted to be wrapped thereabout. The arrangement is such that when the string is pulled the disk may be spun at 60 a high velocity, like a top, the pin 5 forming a bearing wherein there is very little friction. Due to the weight of the disk it has considerable momentum and will spin for a considerable period of time. 65

Arranged about the upper portion of the pan are a plurality of pockets or depressions 14. A toy target 15 may be set in each depression.

I have shown the targets 15 as being in the 70 form of aeroplanes. Each aeroplane 15 is preferably formed from a single piece of sheet metal having a wing portion 16 from which extends a tail portion 17. Extending forwardly from the wing portion 16 is an extension 18 having oppositely extending ears 19 thereon. At 20 is a perforation in this extension. The extension is bent over to form a nose 21, as shown in Figure 2 and the metal folds back upon itself so that the ears 19 are 80 under the tail 17. The ears 19 are bent up over the tail to fasten the parts together. A steel ball 22^a sets in the opening 20 and is located between the lower strip of metal and the upper strip of metal. At the center of 85 the wing portion is a small perforation 22 in which the top of the ball is received. Both the openings 20 and 22 are smaller than the diameter of the ball so that the ball is confined in the metal structure. At the same 90 time the ball is free to rotate so that if the aeroplane is set on an inclined surface it will roll by gravity. When the aeroplane rolls down an incline or flat surface, the tail drags on the surface with enough friction to always 95 cause the nose of the plane to point in the direction the plane is traveling. The construction of the aeroplane is extremely simple. When the aeroplanes are positioned over the 100 pockets 14 the portion of the ball 22^a thereof which projects through the bottom of the aeroplane structure will rest in the pocket, and keep the plane from rolling down the inclined surface. In Figure 1 I have shown three of the aeroplanes in their normal position and have shown the normal position of the other two in dotted lines while the full line position of two of the planes show where the planes will roll when they are knocked out of their respective pockets. In the operation 105

110

of the toy the disk 7 is spun at a high velocity, as previously described. The player rolls steel balls, such as ball bearings, into the passage 10. There may be five or six such balls. 5 When the balls roll into engagement with the disk 7 they will be forced under the outer edge of the disk, and propelled at a high velocity out the passage 11. As long as the disk 7 is revolving at high velocity the balls, 10 designated 23, will travel around the flange 3 at high velocity. They will have sufficient momentum to reenter the passage 10 and have additional force imparted thereto by again passing under the disk 7. As the disk 7 15 begins to slow down the balls will be propelled with a gradually decelerated speed. Finally they will not have sufficient momentum to travel around the outer edge of the pan, and will drop in toward the center of the 20 pan. In dropping in toward the center they will frequently collide with the targets or aeroplanes 15. They are of sufficient size that they will dislodge the aeroplanes, and the aeroplanes will roll down to the lowest 25 part of the pan. Thus in the operation of the toy the series of balls 23 travels several times completely around the pan at high velocity and finally some of them will hit the aeroplanes and knock them down. The action 30 being intended to simulate or suggest the idea of aeroplanes being shot down from the sky, and to carry out this effect, the pan is preferably suitably decorated.

In order to carry out the idea of a game, 35 the aeroplanes, or the pockets for receiving aeroplanes, may be given a number, and the player, after he has spun the disk, will be credited with points corresponding to the sum of the numbers on the different planes, or 40 different pockets. Not only is the action of the toy attractive, but it is also an entertaining game.

Due to the fact that the disk 7 is free to slide up and down on the pivot pin 5, it will 45 always engage the balls 23 with sufficient friction to impart considerable speed and momentum thereto. It is therefore of advantage to have the disk 7 vertically movable within certain limits in order to prevent the balls from 50 jamming when they pass under the disk.

While I have shown and described a particular construction, it will be understood that the invention is not limited to the particular construction and arrangement herein 55 specifically disclosed and that various changes and modifications may be made therein. It will also be understood that the invention is not confined to the use of miniature aeroplanes for targets, as other suitable targets 60 may be employed. It is preferable, however, that a target be provided which is capable of rolling down the inclined surface so as to give additional action to the toy.

I claim:

65 1. In a toy, a flanged pan, and means lo-

cated at one side of the pan for propelling balls around the pan, said means including a spinning disk adapted to frictionally engage the balls.

2. In a toy, a flanged pan, and means located at one side of the pan for propelling balls around the pan, said means including a spinning disk adapted to frictionally engage the balls, said pan being inclined with said means at the lowermost point thereof. 70 75

3. In a toy, a ball propelling device comprising a disk, a pivot on which the disk may be spun, said disk being free to move up and down vertically between certain limits, and means over which balls may roll in passing 80 under the disk.

4. In a toy, a pan, a spinning disk having a portion thereof spaced above the pan, and balls adapted to roll under the disk and be propelled thereby. 85

5. In a toy, a pan, a spinning disk having a portion thereof spaced above the pan, balls adapted to roll under the disk and be propelled thereby, a housing enclosing the disk, a guideway for feeding the balls to the disk 90 and a passageway through which balls may pass from the disk.

6. In a mechanical toy, a substantially circular pan having a flange around the periphery thereof, a disk rotatably mounted on the pan eccentrically thereof, the periphery of the disk being relatively close to said flange, the bottom of the disk being spaced away from the bottom of the pan, and balls adapted to roll around the pan and under the disk. 95 100

7. In a mechanical toy, a substantially circular pan having a flange around the periphery thereof, a disk rotatably mounted on the pan eccentrically thereof, the periphery of the disk being relatively close to said flange, 105 the bottom of the disk being spaced away from the bottom of the pan, and balls adapted to roll around the pan and under the disk, the under surface of the disk being convexed.

8. In a mechanical toy, a substantially circular pan having a flange around the periphery thereof, a disk rotatably mounted on the pan eccentrically thereof, the periphery of the disk being relatively close to said flange, the bottom of the disk being spaced away from the bottom of the pan, and balls adapted to roll around the pan and under the disk, the under surface of the disk being convexed, 110 115 said disk being movable vertically to a slight extent.

9. In a mechanical toy, a substantially circular pan having a flange around the periphery thereof, a disk rotatably mounted on the pan eccentrically thereof, the periphery of the disk being relatively close to said flange, the bottom of the disk being spaced away from the bottom of the pan, and balls adapted to roll around the pan and under the disk, the under surface of the disk being convexed, and a housing substantially enclosing the disk, 125 130

said housing having oppositely extending passageways through which balls may be guided from the pan under the disk, said housing also serving to prevent the balls from 5 engaging the disk except at a desired point.

10. In a toy, a pan, a disk mounted in the pan and having a portion of its under surface spaced above the pan, and balls adapted to roll in the pan and be frictionally engaged 10 by passing between the disk and the pan.

11. In a toy, an inclined dished pan, a disk mounted in the pan and having a portion of its under surface spaced above the pan, and balls adapted to roll in the pan and be frictionally engaged by passing between the disk 15 and the pan, said disk being located at the lowest portion of the pan.

12. In a top, an inclined dished pan, a disk mounted in the pan and having a portion of its under surface spaced above the pan, and balls adapted to roll in the pan and be frictionally engaged by passing between the disk and the pan, said disk being located at the lowest portion of the pan, said pan having 25 a flange around the edge thereof, and having a series of recesses in the upper portion thereof, and a target adapted to roll over the inclined pan received in each recess.

13. A toy target comprising a sheet metal 30 frame, and a ball in the frame with a portion thereof projecting through the frame and adapted to provide a rolling surface for the target whereby the target may roll by gravity over an inclined surface, said target having a rearwardly extending portion adapted 35 to drag on the surface over which the target rolls, whereby one end of the target will always point itself in the direction in which the target is rolling.

14. A toy target in the form of an aeroplane comprising a continuous length of sheet metal folded upon itself to provide upper and lower portions, lateral projections on the upper portion to represent wings, a ball retained between the upper and lower portions 40 and projecting through an opening in the lower portion of less diameter than the diameter of the ball to provide a rolling surface for the target, the ends of the portions being 45 clipped together.

15. In a toy, a flanged pan inclined toward one side thereof and having a target retaining detent therein, means located at one side of the pan for propelling balls thereabout, and a target element adapted to roll on the 50 inclined pan retained in said detent.

16. In a toy, a flanged pan having a plurality of target retaining detents therein, a target element in each detent adapted to move over the surface of the pan, and means for 60 propelling a ball around the pan, a portion of the pan being sloped whereby the ball will roll away from the flange as it loses momentum, said target retaining detents being located on the inclined portion of the pan. 65

17. In a mechanical toy, a flanged disk which is dished, means at one side of the pan for propelling balls thereabout, said disk having a plurality of target retaining recesses therein, a target adapted to roll by 70 gravity retained in each recess and adapted to be released from the recess by contact of a ball therewith, said recesses being spaced inwardly from the flange about the disk.

In testimony whereof I have hereunto set 75 my hand.

HARRY E. McCOY.

CERTIFICATE OF CORRECTION.

Patent No. 1,715,166.

Granted May 28, 1929, to

HARRY E. McCOY.

It is hereby certified that error appears in the printed specification of the above numbered patent requiring correction as follows: Page 3, line 18, claim 12, for the word "top" read "toy"; and that the said Letters Patent should be read with these corrections therein that the same may conform to the record of the case in the Patent Office.

Signed and sealed this 2nd day of July, A. D. 1929.
